[57] CLAIM

The ornamental design for a pneumatically propelled captive carrier, as shown and described.

DESCRIPTION

FIG. 1 is a perspective view of the top, left side and front of the ornamental design for a pneumatically propelled captive carrier of this invention, showing the cover thereof in its closed position;

FIG. 2 is a perspective view of the top, left side and front of the ornamental design for a pneumatically propelled captive carrier of this invention, showing the cover thereof in its open position;

FIG. 3 is a front elevational view of FIG. 1;

FIG. 4 is a right side elevational view thereof, with the left side elevational view being a mirror image thereof;

FIG. 5 is a rear elevational view thereof;

FIG. 6 is a top plan view thereof, showing the cover closed, with the bottom plan view, with its cover closed, being a mirror image thereof; and,

FIG. 7 is a top plan view thereof, showing the cover open, with the bottom plan thereof, with its cover open, being a mirror image thereof.

FIG. 1

FIG. 2

FIG. 3

FIG. 4

FIG. 5

FIG. 6

FIG. 7
